Warren G. Ogden

UNITED STATES PATENT OFFICE.

FREDERICK L. MACDONALD, OF WALTHAM, MASSACHUSETTS.

GOLF-BAG APPLIANCE.

Application filed April 18, 1923. Serial No. 632,875.

To all whom it may concern:

Be it known that I, FREDERICK L. MACDONALD, a citizen of the United States, residing at Waltham, in the county of Middle-

sex and State of Massachusetts, have invented certain new and useful Improvements in Golf-Bag Appliances, of which the following is a specification.

This invention relates to golf bags and more particularly to an appliance for attachment to golf bags to facilitate handling the clubs, either by the player or the caddy, when playing a game.

Golf bags are now generally provided with a handle, of the satchel type, and with a limp shoulder strap. Whenever a player, who "totes" his own clubs, makes a stroke, he lays down his bag on the ground necessitating stooping after each stroke to pick up the bag by the strap or the handle. This is tiring, especially on the older players, and the time expended in laying down and picking up the bag slows up the game to an extent that is disadvantageous to the following players when the course is crowded.

The object of the present invention is to overcome the difficulties just referred to in a simple and inexpensive manner. Accordingly a feature of the invention comprises an auxiliary or supplemental handle for a golf bag, of negligible weight, so constructed and arranged that the bag can be dropped to the ground and instantaneously lifted therefrom without stooping, or other change of posture, by the player.

To the accomplishment of this object the invention comprises the features and combinations of parts described in detail hereinafter and then defined in its true scope by the appended claims.

The preferred form of the invention is illustrated in the accompanying drawing in which:

Figure 1 is a perspective view of a golf bag lying on the ground having the new handle applied thereto, and shown in raised position, full lines, and folded for carrying the bag, dotted lines; Fig. 2 is a perspective view of the auxiliary handle of Fig. 1 detached from the bag; Figs. 3 and 4 illustrate details, in plan and rear elevation, of the preferred construction for automatically retaining the handle in either its raised or folded position; Fig. 5 is a detail showing a modification of the ground rest for quick adjustment to fit golf bags of varying di-

meter; and Fig. 6 is a plan view of the handle illustrating the action of modified handle retaining and stop construction, with the handle raised as in Fig. 1.

In the embodiment of the invention illustrated by Figs. 1 and 2 of the drawing the appliance comprises three main parts namely, a handle preferably in the form of a U-shaped bar 10, a support comprising a ring clasp 12, and a ring locking bar 14. The clasp 12 is in the form of a split ring which embraces the leather reinforce at the open end of the golf bag 16 just below the usual stiffening ring 18. In attaching the appliance it is preferably, but not necessarily, so adjusted angularly that when the handle 10 is folded against the bag (see dotted lines Fig. 1) it will lie at the side of the bag which is against the body when carrying the bag by its shoulder strap 20, or tucked under the arm. Such a location will be found to be the most convenient in manipulating the handle as the bag is slipped to the ground and it also keeps the handle away from the ball pocket when folded down.

The split ring clasp 12 comprises a flat band having two semi-circular flexible arms 22 (Fig. 2) each terminating in an outturned end 24, lying in the same plane, and engaged by the ring locking bar 14. The two other ends of the band arms 22 terminate at the lug-like ends of a housing 26 which is located diametrically opposite the center of the bar 14. The ring clasp is made of brass or like metal and is sprung on the head of the golf bag, as shown in Fig. 1. The locking bar, also of brass or other metal, is provided with looped ends 28 (Figs. 1 and 2) which form sockets within which the outturned band ends 24 of the ring clasp may be seated and thus hold and clamp the ring tightly to the bag. The bar 14, when in place, serves as a ground rest to keep the bag from rolling and, being opposite the handle 10, maintains the auxiliary handle in its vertical position as shown by Fig. 1, or perpendicular to the bag.

The handle 10 may be made from metal tubing, to secure lightness of construction, as shown by Figs. 2, 3 and 4. The two free ends 30 are each inturned and enter loosely through circular apertures in the end walls of the ring clasp housing 26 being connected within the housing by a coiled spring 32, in the manner shown. In order to provide

for automatically locking or retaining the handle in either of its positions the end walls of the housing 26 are provided with recesses in the form of grooves 25 and 27 (Figs. 3 and 4) extending, respectively, from the aperture for receiving the handle to the top wall and rear wall of the housing. When the bag is on the ground the handle ends 30 are held in the grooves 25 (see Fig. 10 3) by the spring 32 and when the handle is folded down the spring, in like manner holds the ends 30 in the grooves 27 (see Fig. 4). Since the handle ends 30 are held yieldingly together by the spring they can yield 15 outward in moving from one position to the other and readily cam past the intervening projecting corner 29 of the housing. Lugs 31 may be provided at the upper forward corners of the housing to prevent an overthrow of the handle when raised.

A modified form of handle locking means is illustrated by Fig. 6 in which each handle end 30 is made solid and is provided with a 20 socket 34 at its inner side. In each end wall of the housing there is an outwardly projecting locking pin 36. These pins are directly above the apertures through which the handle ends 30 enter so that when the handle is raised from its position against 25 the bag the pins 36 will hold it in a position perpendicular to the bag by seating in the sockets 34. A stop lug 38 projects from one housing end wall at the forward side of the handle end 30 and functions to prevent a 30 forward overthrow of the handle as the bag drops to the ground. A like stop lug 40 projects from the other housing end wall, at the rear side of the handle end 30 and functions to hold the handle against the bag 35 when folded thereagainst. The central spring 32 permits the handle end to yield outwardly and cam past the lug 40 as the handle is raised to vertical position. The handle ends also cam past the two pins 36 40 until the sockets 34 register therewith and then the spring 32 draws the handle ends inward causing the pins to seat in the sockets and thus lock the handle in its upright 45 position. Preferably the housing 26 is a casting having the constructional features 50 for either form just described.

A modified form of the ring locking bar 19 is shown by Fig. 5. Golf bags are not of standard size and in order to obviate manufacture of the novel appliance in a number of sizes, the bar 14 may be made in two parts 55 42 and 44 detachably held together in any convenient manner, as by the screws shown, which may be inserted in one or another of the pairs of registering holes 46 according 60 to the length desired for the bar as the diameter of the ring 12 is changed. In either form of locking bar, after having been slipped over the outturned band ends 24, the 65 parts may be bolted securely together as il-

lustrated, although in practice the frictional fit of the parts has ordinarily been found to give sufficient holding power.

It will be observed that in carrying the bag the ground rest 14 is away from the body and the curved hand-hold 48 causes the tubular handle 10 to hug the bag and thus be unprotruding. After selecting a club for a shot the player's hand naturally seizes the hand-hold 48 and, as the bag drops to the ground, the handle lifts to its vertical position and is automatically retained in this position by the locking means described. The length of the handle is such that the hand-hold 48 is at such a height that it may 70 be seized, without stooping, to lift the bag. The flexible ring 12 is thin and light in weight and the bar 14, while somewhat thicker to resist bending, still is light in weight. The light weight tubular handle 10 75 completes the number of parts added to the bag. The small additional weight is unnoticeable in handling the bag and is wholly outweighed by the convenience and comfort afforded by the use of the appliance. When 80 consideration is given to the fact that the use of the novel appliance eliminates about one hundred "stoops" in the average 18 hole game, for stroking or changing clubs, the advantage gained will readily be apparent. 85 The construction is simple and inexpensive, acts automatically and accurately, and can be almost instantaneously applied to any 90 golf bag.

While the particulars of construction 100 herein set forth are well suited to one form of the invention, it is not to be understood that these particulars are essential since they may be variously modified within the skill of the artisan without departing from 105 the true scope of the actual invention as defined by the following claims.

What is claimed as new is:—

1. An appliance for golf bags comprising a ring clasp to fit about the head of a bag, 110 a handle secured at one side of said clasp for folding against the bag, and a combined clasp retainer and ground rest at the other side of said clasp.

2. An auxiliary handle for golf bags comprising a generally U-shaped bar the legs of which are inturned at their free ends, a support to be secured to the bag having apertured lugs to loosely receive said inturned ends, a spring connecting said ends and yieldingly drawing them together, and means for retaining the handle in a selected relation to the support. 115 120

3. A golf bag appliance comprising a flexible band split at one side with its ends outturned, a bar having inturned ends forming sockets to receive said band ends and hold the band in position when sprung on a golf bag, and a handle at the side of the band opposite the bar. 125 130

4. A golf bag appliance comprising a flexible band split at one side with its ends outturned, a bar having inturned ends forming sockets to receive said band ends and hold the band in position when sprung on a golf bag, means to vary the length of said bar whereby to vary the size of the band, and a handle mounted on said band opposite the bar. 25
- 5 10 5. The combination with a golf bag of a ring clasp adjacent its open end, an elongated bar secured to said clasp and serving as a preventative against rolling when the bag lies on the ground, and an auxiliary bag handle pivotally mounted on said clasp, diametrically opposite said bar, for folding against the bag when not in use and for being turned into perpendicular relation to the bag as it is dropped to the ground. 30
- 15 20 6. An appliance for golf bags comprising a support having provision for attachment to a golf bag, a handle of substantial length hinged to said support and movable to lie along the outer side of the bag or stand out from the bag within ready reach of a player without stooping, and a rest projecting from said support and for engagement with the ground to prevent rolling of the bag and consequent rocking of the handle to the ground. 35
7. A golf bag appliance comprising an auxiliary handle, a clasp connected to the handle having a pair of arms adapted to receive a golf bag and means cooperating with said arms whereby the clasp may be adjustable to fit bags of different diameters. 40
8. A golf bag appliance comprising an auxiliary handle, a clasp connected to said handle having overlapping portions adjustable to vary the extent of their overlap that the clasp may fit bags of different diameters and means to secure said overlapping portions together in their different positions of adjustment. 45

FREDERICK L. MACDONALD.
